UNITED STATES PATENT OFFICE.

FELIX TARRANT HOWELL, OF BIRMINGHAM, ALABAMA.

STEAM SEPARATOR AND TRAP.

SPECIFICATION forming part of Letters Patent No. 555,701, dated March 3, 1896.

Application filed August 19, 1895. Serial No. 559,736. (No model.)

To all whom it may concern:

Be it known that I, FELIX TARRANT HOWELL, a citizen of the United States, and a resident of Birmingham, in the county of Jefferson and State of Alabama, have invented certain new and useful Improvements in Steam Separators and Traps, of which the following is a specification.

My invention relates to an apparatus that automatically separates water from steam, and by allowing only dry steam to go to the cylinders or steam-receivers secures the maximum of economy, efficiency, and safety.

Boilers overworked constantly or forced through sudden demands or emergencies are apt to foam or send off watery and non-elastic vapors, and long lines of pipe, uncovered pipe, and improperly-drained pipe are partially filled or pocketed with water of condensation.

Steam-traps or water-drip pipes interposed in the line of the steam-pipe near the cylinders or steam-receivers have been employed heretofore comprising floats and controlling-valves for opening the said trap and allowing the water to escape at proper intervals.

While quite simple and quickly responsive in action to requirements the float has under certain conditions proved inadaptable for use under very high pressures, as the tendency is to hold the float and its valve more firmly down to its seat under very high pressures than under less pressures.

To better adapt a float-controlled valve for steam-traps to the various conditions above suggested, and for other reasons which will suggest themselves or will be hereinafter suggested, I have made certain novel arrangements and combinations of devices hereinafter described and claimed, and besides have adapted my improved device to operate more quickly to better prevent the steam from escaping with the water of condensation when the water-drip valve is employed. I also provide means for indicating the amount of water accumulated in the trap and also to better facilitate the construction and operation of said trap, as will hereinafter appear.

In the accompanying drawings, Figure 1 is a side elevation of my improved separator with pipe connection for attachment to the boiler and engine; Fig. 2, a vertical central section thereof with the float-valve closed, and

Fig. 3 a similar view of the lower part of the trap with the said valve open.

A is a spheroidal casing made in two sections, consisting of a base-section A' and a cap-section A² united by flanges *a* and bolts *a'*. The base-section A' has a neck A³ to provide a valve-seat A⁴ and a base-flange A⁵ extending therefrom, which serves as a support for the casing and may be secured to any suitable support by bolts passing through the said base-flange.

A steam-pipe B leading from the boiler enters the lower part of the cap-section A² by double-reversed elbows B' B², connected by a nipple B³, and empties the contents of the pipe downwardly into the base-section A', the heavy watery vapors and products of condensation being deposited in the bottom of the said base-section, and the dry steam passing upwardly to the top of the cap-section A² and entering the end of the upturned pipe-joint C is conducted to the cylinder of a steam-engine, to the receiver of an air-brake, or for other purpose where dry steam is required.

A condensed-water-discharge pipe D is fitted to the neck A³ of the base-section A' below the valve-seat A⁴, and a valve E adapted to fit the seat A⁴ is secured to a stem E', guided in a cross-bar *e'* in the neck A³ and secured to the bottom of a hollow spherical float F. A stem E², secured to the top of said float, is guided in a top cross-bar, *e'*, supported in depressions between the flanges *a* of the casing-sections A' A², by which means the float may be easily operated by the pressure of the water accumulating in the bottom of the base-section A' of the casing A. When the steam-pressure is excessive, the float F, if not otherwise acted upon than by the steam and water, would be forced down by the steam and hold the valve E closed securely upon its seat and thus prevent the water of condensation from escaping. To counteract this force, the valve-stem E' is supported upon the short arm F' of a lever F, fulcrumed upon a bracket *f*. The lower end of the stem E' has packed bearings in the lower end of the discharge-pipe, and a smaller discharge-pipe D' is fitted and projects from one side of the discharge-pipe D, and thus the lower end of the valve-stem E' projects from the pipe D, is packed by means of a stuffing-box *f'* in the usual way, and is

controlled by the long arm f^2 of the lever F, which is fitted with a weight G and graduated to correspond with the steam-pressures under which the valve is loaded to operate. The 5 float F, when thus relieved of the excessive steam-pressure, will be lifted by its buoyancy when the water reaches a sufficient height within the chamber A, and the valve E being thus lifted the accumulated water of condensation will quickly escape. A water-gage H, comprising an upper screw-plug, H', and a stop-cock h^1 , a lower screw-plug, H², stop-cock h^2 , and escape-cock h^3 , supports a water-glass H³ in a well-known manner, both attached to 10 the entire lower section A' of the casing A. A water-petcock I in the bottom of the section A' of the casing, close to the neck A³ and valve-seat A⁴, will provide means for discharging the condensed water from the casing A, in whole 15 or in part, to prevent it from freezing in the casing should the steam be shut off, and also for letting off the water to allow it to remain at any required height indicated by the glass gage. The opening to the petcock I is shown 20 in the drawings to be covered by a projection e from the valve E, and when the said valve is raised by lifting the float or operating the safety - valve lever the water may be discharged through the said petcock, should the 25 drip-water pipe become frozen or otherwise obstructed. The petcock may on such occasions be left open and the separator will automatically discharge through the opening therein whenever the check-valve is raised. 30 It will be readily perceived that the lower section of the casing, containing the movable parts and parts liable to become obstructed 35

with grease, sediment, or otherwise, may be readily removed from the upper section without breaking the steam connections, a rubber 40 gasket between section A' and A² providing simple, inexpensive, and ready means for making the said connections.

I claim as my invention and desire to secure by Letters Patent—

1. A steam-trap comprising the casing made in two sections A', A², the steam-receiving pipe entering the cap-section A² from a downwardly-turned nozzle, a discharging steam-pipe leading from the top of section A² with 50 a U-shaped nozzle, the discharge-section having a base-flange and neck connecting the same therewith having a valve-seat, a guide-bar fitted therein, a valve seated thereon, a valve-stem, float, for actuating the said valve 55 and an upper guide-bar held between the section-casings, substantially as described.

2. A steam-trap comprising a casing, the steam-receiving pipe, the steam-discharge pipe, the drip-water pipe, the check-valve 60 therein and float for actuating said valve, and a petcock covered by the said valve and adapted to allow the water to be drawn from the casing, independently of the check-valve, when the float is raised, substantially as de- 65 scribed.

In testimony that I claim the foregoing as my invention I have signed my name in the presence of two subscribing witnesses.

FELIX TARRANT HOWELL.
